UNITED STATES PATENT OFFICE

HARRY HUTHMACHER, OF IRVINGTON, NEW JERSEY

TIMING MECHANISM

Application filed December 30, 1927. Serial No. 243,684.

This invention provides for the automatic starting and stopping of a radio receiver, whereby a set otherwise tuned may be brought into action at a predetermined time to receive a desired program, or may be cut off at a given time when further reception is not required. Thus, a certain program may be received and further reception cut off after the elapse of a certain period of time.

10 In carrying out the invention an ordinary alarm clock of any make is employed, and the hammer is included in the filament circuit of the radio receiver to make or break the filament circuit as required. A controlling 15 switch is included in the time circuit and may be set to start or stop the receiver, or adjusted to a neutral point as the occasion may demand.

20 While the drawing illustrates a preferred embodiment of the invention it is to be understood that in adapting the means to meet specific needs and requirements the design may be varied and changes in the minor details of construction may be resorted to within 25 the scope of the invention as claimed, without departing from the spirit thereof.

For a full understanding of the invention and the merits thereof, reference is to be had to the following description and the drawing 30 hereto attached, in which,—

Figure 1 is a top plan view of a mechanism embodying the invention.

Figure 2 is a schematic view, illustrating the circuits.

35 The numeral 1 denotes an ordinary alarm clock and 2 the usual hammer thereof. A spring contact 3 is mounted upon the frame of the clock adjacent the hammer 2, and is connected to a binding post 4, which is attached to the clock frame but electrically insulated therefrom. A clip 5 is attached to the binding post 4. An arm 6 is attached to the frame of the clock adjacent the hammer 2, and is formed with a hook 7 which is adapted 40 to engage a stop 8 carried by the hammer 2. The arm 6 is connected to the binding post 9 attached to and electrically insulated from the frame of the clock. A clip 10 is attached to the binding post 9. The hammer 2 is disposed between the contact 3 and arm 6 and

is normally in engagement with the contact 3.

A binding post 11 is mounted upon the frame of the clock and electrically insulated therefrom. A pig tail 12 or other flexible conductor connects the binding post 11 and 55 hammer 2.

The numeral 13 designates a suitable base upon which the alarm clock 1 is mounted. Binding posts 14 and 15 are mounted upon the base 13. A switch is likewise mounted 60 upon the base 13 and comprises taps 16, 17 and 18 and a pivoted arm 19. A wire 20 connects the tap 18 with the clip 10. A wire 21 connects the tap 16 with the clip 5. A wire 22 connects the binding post 15 with the 65 pivoted arm 19.

The numeral 23 designates a radio receiver which may be of any make. The receiver is of the type including tubes. The terminals of the filament circuit are designated by the numerals 24 and 25. The usual A-battery is designated by the numeral 26. A wire 27 connects one pole of the A-battery with the filament terminal 24, and a wire 28 connects the other pole of the battery with the binding post 15. The wire 29 connects the binding post 14 with the other terminal 25 of the filament circuit. The mechanism appears substantially as shown in Figure 1 of the drawings, and may be used in connection 80 with any radio receiver including a filament circuit. It is only necessary to connect the binding posts 14 and 15 with the A-battery and filament circuit substantially in the manner herein indicated and shown in Figure 2 85 of the drawings. When the switch arm 19 is moved to connect with the tap 17 the switch is neutral and the timing mechanism inactive. As hereinbefore stated the hammer 2 is normally in engagement with the contact 90

3, and when the switch arm 19 is adjusted to make contact with the tap 16 the filament circuit is closed, and the radio receiver 23 in condition for reception. The circuit is as follows: Starting at the tap 16 the current 95 flows through the wire 21, contact 3, hammer 2, wire 12, wire 30 between the binding posts 11 and 14, wire 29, filament circuit of the radio receiver in the manner well understood, thence through wire 27, battery 26, wires 28 100

and 22, and switch arm 19 to the contact or tap 16. It is assumed that the alarm circuit has been set for a given time, and when the predetermined time has been reached the 5 alarm mechanism is set off in the accustomed way, and at the first movement of the hammer 2, the filament circuit is broken by the hammer leaving the contact 3. The hammer 2 is held away from the contact 3 by the stop 8 engaging the hook 7 of the arm 6. In this 10 manner the reception is stopped, since the filament circuit of the receiver is broken. To start the radio at a predetermined time the switch arm 19 is adjusted to make contact with the tap 18. The filament circuit of 15 the radio receiver is interrupted by the break between the arm 6 and hammer 2, as indicated most clearly in Figure 2 of the drawings. When the hammer 2 is released at the 20 predetermined time by the alarm mechanism of the clock going off, the filament circuit of the receiver is closed by the hammer 2 leaving the contact 3 and closing the circuit through the arm 6 which engages the stop 8 in 25 the manner previously described. The circuit is as follows:—Starting from the contact 18 through wire 20, arm 6, hammer 2, wire 12, post 11, wires 30 and 29, filament circuit of the receiver, thence through wire 27, 30 battery 26, wires 28 and 22, switch arm 19, and tap 18. It will thus be understood that the radio receiver may be set to start at a given time or when started to stop at a predetermined time, without requiring any particular attention, other than setting the controlling switch.

While the invention is disclosed in connection with a radio receiver for which it is particularly designed, it is observed that it 40 is not the intention to so limit its use as it is adapted for other applications where electric circuits are to be opened or closed at predetermined periods.

Having thus described the invention, I 45 claim:

1. A timing mechanism for making and breaking a filament circuit, the same including an alarm clock having its hammer element forming a part of the circuit, contact 50 elements at opposite sides of the hammer element and forming parts of the circuit, a switch for setting the circuit to start or stop the mechanism controlled thereby, and stop means to engage the hammer element when moved from one of the said contact elements to the other and holding it in the engaged position.

2. An electric timing mechanism including an alarm clock adapted to have its hammer 60 included in a circuit as a part thereof, contacts at opposite sides of the hammer and forming terminals of the circuit, and stop means to engage the hammer when moved from one of the said contacts to the other to 65 hold it in the engaged position.

3. An electric timing mechanism including an alarm clock, a binding post on the frame of the clock, a flexible conductor connecting the binding post with the hammer of the clock, contacts at opposite sides of the hammer and forming terminals of the circuit to be closed or broken by the hammer, one of the contacts being normally in engagement with the hammer, and interengaging means between the other contact and the hammer to hold the latter when moved from a normal position.

In testimony whereof I affix my signature.
HARRY HUTHMACHER. [L.S.]
